(57) **CLAIM**

The ornamental design for an opaque insert for an arthropod trapping device, as shown and described.

DESCRIPTION

FIG. 1 is a front, right-side isometric view of an embodiment of an opaque insert for an arthropod trapping device;

FIG. 2 is a rear, left-side isometric view of the opaque insert for an arthropod trapping device of FIG. 1;

FIG. 3 is a front view of the opaque insert for an arthropod trapping device of FIG. 1;

FIG. 4 is a right side view of the opaque insert for an arthropod trapping device of FIG. 1;

FIG. 5 is a rear view of the opaque insert for an arthropod trapping device of FIG. 1;

FIG. 6 is a left side view of the opaque insert for an arthropod trapping device of FIG. 1;

FIG. 7 is a top view of the opaque insert for an arthropod trapping device of FIG. 1; and,

FIG. 8 is a bottom view of the opaque insert for an arthropod trapping device of FIG. 1.

The broken lines illustrate structure or features that form no part of the claimed design.

The drawings include shadows and reflections that indicate contour, not surface ornamentation.
